(57) **CLAIM**

The ornamental design for a round clutch core guard, as shown and described.

DESCRIPTION

FIG. 1 is a front perspective view illustrating one embodiment of my design for a round clutch core guard;

FIG. 2 is a left view thereof;

FIG. 3 is a top view thereof;

FIG. 4 is a right view thereof;

FIG. 5 is a bottom view thereof;

FIG. 6 is a rear view thereof;

FIG. 7 is a rear perspective view thereof; and

FIG. 8 is a front perspective view thereof.

FIG. 9 is a front view illustrating another embodiment of my design for a round clutch core guard;

FIG. 10 is a left view thereof;

FIG. 11 is a top view thereof;

FIG. 12 is a right view thereof;

FIG. 13 is a bottom view thereof;

FIG. 14 is a rear view thereof;

FIG. 15 is a rear perspective view thereof; and,

FIG. 16 is a front perspective view thereof.

The broken lines illustrate portions of the round clutch core guard, which forms no part of the claimed design.
